INVENTOR
HORACE T. THOMAS

BY

Palmonard A. Parker
HIS ATTORNEY.

UNITED STATES PATENT OFFICE.

HORACE T. THOMAS, OF LANSING, MICHIGAN.

SOCKET-PLUG.

1,323,659.

Specification of Letters Patent.

Patented Dec. 2, 1919.

Application filed March 31, 1919. Serial No. 286,573.

To all whom it may concern:

Be it known that I, HORACE T. THOMAS, a citizen of the United States, residing at Lansing, county of Ingham, State of Michigan, have invented a certain new and useful Improvement in Socket-Plugs, and declare the following to be a full, clear, and exact description of the same, such as will enable others skilled in the art to which it pertains to make and use the same, reference being had to the accompanying drawings, which form a part of this specification.

My invention relates to socket plugs and a specific object of my improvements is to provide an improved connector for automobile head light and battery circuits, that may be readily and cheaply assembled and the parts of which shall not readily become loose in use.

I secure this object in the device illustrated in the accompanying drawings in which,

Figure 1 is a section on a plane through the axis of a plug embodying my invention.

Fig. 2 is a detached elevation of the connecting wire.

Fig. 3 is a view of the parts shown in Fig. 2 looking from the left of the latter figure.

Fig. 4 is a detail sectional view of the end of the socket.

Fig. 5 is a side elevation of the parts shown in Fig. 2.

Fig. 6 is an end view of the metal casing.

Fig. 7 is an axial view of the metal casing.

Fig. 8 is a view similar to Fig. 1 showing a modified construction.

a is the usual conducting wire surrounded by insulating material *a*³ and having its end flattened at *a*² to form a connecting and retaining means.

b is a cylindrical piece of insulating material having at one end the annular laterally extending flange *b*² and fitting closely over the covering *a*.

c is a metal casing adapted to fit over and closely engage the insulating cylinder *b* at *c*³ toward the end remote from the flange *b*². The casing *c* is enlarged and is bent outward at *c*² to the diameter of the periphery of the flange *b*² and it extends over the rest of the cylinder *c* and over the periphery of the flange *b*². *c*³ are apertures through the wall of the casing *c* just within the flange *b*² of the cylinder *b*.

d is a wire engaging upon the cylinder *b* and having its ends turned outward at right angles at *d*² *d*² to extend through the apertures *c*³ *c*³ and project from the casing *c*. The wire *d* extends longitudinally along the outer wall of the cylinder *b* to a point adjacent to the shoulder *c*² in the casing *c*. It then extends in a semi-circle around said cylinder forming an arc joining two parts *d*³ *d*³.

The method of assembling the plug above described is as follows:

The ends *d*² *d*² of the wire *d* are sprung together and the wire is inserted in the casing *c* with its arcuate portion *d*⁴ adjacent to the shoulder *c*² and the ends are allowed to spring outward which projects them through the apertures *c*³ *c*³ of said casing. The cylinder *b* is now inserted in the casing *c* confining the portions *d*³ *d*³ *d*⁴ of the wire *d* between its outer wall, the enlarged portion of said casing, the flange *b*² and the shoulder *c*² so that the projecting ends *d*² *d*² cannot be forced inward.

The conductor *a* *a*³ is now inserted and permanently fixed in the insulating cylinder *b* as shown.

The socket *e* is of the conventional construction having the bayonet slot *e*² and the contact spring *e*³.

The plug is inserted into said socket, the projecting ends *d*² *d*² of the wire *d* engaging in the slots *c*² and the end *a*² of the wire *a* engaging the contact point upon the spring *e*³.

Obviously two wires may be used, as shown in Fig. 8, instead of one.

What I claim is:

1. In an apparatus of the kind described, a conductor, a covering of insulating material around said conductor, a wire having an outwardly extending end engaging against the outer surface of said insulating cover and a protecting casing surrounding said wire and said cover, the ends of said wire extending through said casing.

2. In an apparatus of the kind described, a conductor, an insulating cover surrounding said conductor, a wire having its ends bent outward, said wire engaging against the outer surface of said cover and extending partly around the same intermediate its out-turned ends, and a casing surrounding said wire and cover, the ends of said wire extending through said casing.

3. In an apparatus of the kind described,

a conductor, an insulating cover around said conductor, a wire having outwardly extending ends engaging against the outer surface of said cover, the portion of said wire 5 intermediate its ends extending longitudinally along the surface of said cover then extending part way around said cover, then extending longitudinally along the surface of said cover parallel to the first mentioned 10 longitudinally extending portion, and a casing surrounding said cover and wire.

4. In an apparatus of the kind described, a conductor, an insulating cover around said conductor, a wire having outwardly extending ends engaging against the outer surface 15 of said cover, the portion of said wire intermediate its ends extending longitudinally along the surface of said cover then extending part way around said cover, then extending longitudinally along the surface of said cover parallel to the first mentioned longitudinally extending portion, a casing surrounding said cover and wire, said insulating 20 cover being provided with an outwardly extending flange around one end, said casing engaging the surface of said cover at one end and being enlarged to extend over said wire and extending over the periphery 25 of said flange at the other end, the walls

of said casing being provided with apertures to permit the passage of an outwardly extending end of said wire. 30

5. In an apparatus of the kind described, a conductor, a cover surrounding said conductor coaxial therewith and having an outwardly extending flange, a wire engaging against the outer surface of said cover and having an outwardly extending end, a casing engaging the outer surface of said covering and the outer surface of said flange 35 and surrounding said wire, its wall being provided with an aperture through which the end of said wire extends for the purpose described. 45

6. In an apparatus of the kind described, a conductor, an insulating cover for said conductor coaxial therewith, a wire engaging against the outer surface of said cover and having an outwardly extending end, a casing surrounding said cover and engaging 50 its outer surface and inclosing said wire, the wall of said casing being provided with an aperture through which the outwardly extending end of said wire projects for the purpose described. 55

In testimony whereof I sign this specification.

HORACE T. THOMAS.
